UNITED STATES PATENT OFFICE.

MARCUS L. HORTON, OF CLAREMONT, NEW HAMPSHIRE, ASSIGNOR TO
SIDNEY SMITH, OF GREENFIELD, MASSACHUSETTS.

IMPROVEMENT IN COOK-STOVES.

Specification forming part of Letters Patent No. **50,072**, dated September 19, 1865.

To all whom it may concern:

Be it known that I, MARCUS L. HORTON, of Claremont, in the county of Sullivan and State of New Hampshire, have invented a new and Improved Mode of Conveying Heated Air to the Elevated Oven of a Cooking-Stove; and I do hereby declare that the following is a full and exact description thereof, reference being had to the accompanying drawings, and to the letters of reference marked thereon.

The nature of my invention consists in providing the lower part of the oven with a conducting-pipe and cap combined, which pipe will convey heated air into the oven to equalize its temperature and act as an absorbent of moisture, and an improved air-flue the whole width of the stove, to allow the air to come in contact with more heating-surface of the stove to increase its temperature and draft.

To enable others skilled in the art to make and use my invention, I will proceed to describe its construction and operation.

In the accompanying drawings, Figure 1 is a top view of the stove with the oven removed. Fig. 2 is a section through the fire-chamber, fire-flues, oven, &c., on the line 2 2, Fig. 1. Fig. 3 is a section through the hot-air flues on the lines 3 3, Fig. 1. Fig. 4 is a cross-section through the fire-chamber, showing the grate-bars. Fig. 5 is a section through the oven on the line 1 1, Figs. 1 and 3. The black arrows indicate the direction of the air-currents. The red arrows show the fire-currents.

M is the fire-chamber.

B are the hollow grate-bars, the air-spaces in which communicate with the external air through the holes D, Figs. 2, 3, and 4, and with the space S behind the back plate of the fire-chamber. From this space S a flue, c c c, the whole width of the stove, extends back to and communicates through the pipe E into the oven R, and with the flues F F inclosing the oven R entirely, which establish a connection between the hot-air flue and oven. From the flue F F, on the top of the oven, are openings J J, through which the heated air may be carried through pipes or flues to other places.

Extending back from the fire-chamber on each side of the stove are the fire-flues m m, communicating through openings n with the flues G, also surrounding and inclosing the oven R, and occupying the space between its sides and the hot-air flues F F. A collar, F',

affords the means of connecting the flues G G with the chimney by a pipe.

In the center of the top of the oven is a ventilator, H, opening into the flues G G and covered with a hood, O, Figs. 3 and 5, to keep anything from falling in from the chimney, and furnished with a valve, y, on the inside of the oven for regulation or completestoppage. The flame and gaseous products of combustion pass along the flues m through the openings n into the flues G G on each side of the oven, and pass up over it into the chimney through the opening I. At the same time cold air rushes in through the openings D into the hollow grate-bars, and passes into and along the flue C until a portion rises into the oven through the pipe E. The rest rises into the flues F F, to be conducted away from the opening J above the oven to wherever it may be desired. The hot air does not fall in temperature in its passage through its flues, as it is kept hot by its proximity to the fire-flues.

I am aware that a stove has been made with the grate-bars B, space S, a flue about one-third the width of the stove in the center, flues F F, with openings each side of the oven R for the heated air to enter it from the flues F F, and their various connections, except what I now claim—viz., the pipe E, for conducting the heated air into the oven from the flues C, so that the spaces at each side of the oven can be omitted, in order that the air which is conveyed away for the purpose of giving warmth elsewhere may be free from the smoke and gases in the oven during the baking process; also, the cap A, Figs. 3 and 5, combined with the pipe E, which cap is to prevent anything from falling into the flue C from the oven; and also the improved flue C, extending the whole width of the stove, thereby increasing the draft of the air-currents as well as exposing them to more heating-surface of the stove.

Having thus fully described my invention, and distinguished between what is admitted to be old and what is claimed to be the improvement, what I claim as new, and desire to secure by Letters Patent, is—

The pipe E with cap A and improved flue C, as arranged and in combination, operating as described, and for the purposes set forth.
